UNITED STATES PATENT OFFICE.

DENNIS MITCHELL, OF WATERLOO, ENGLAND.

FOOT-SOCK.

1,141,814.

Specification of Letters Patent.

Patented June 1, 1915.

Application filed July 20, 1914. Serial No. 851,940.

To all whom it may concern:—

Be it known that I, DENNIS MITCHELL, a subject of the King of England, residing at 6 Glenwyllin road, Waterloo, in the county 5 of Lancaster, England, have invented a new and useful Improved Foot-Sock, of which the following is a specification.

This invention has reference to socks for 10 wearing on the feet; and has for its object to provide a sock which, while it keeps the feet warm and in good condition, will provide for carrying off of perspiration or moisture.

According to this invention, the sock consists of a sole piece proper, and a cap in the 15 front, extending down a substantial proportion of the sole; and it is made of a more or less solid material (not textile fabrics and the like), such as wash leather, or other soft leather or artificial leather, or like material, and is provided with apertures of substantial size, at suitable and substantial distances apart; so that while the greater part 20 of the sock is of solid material, which will keep the feet warm, it enables air, by way 25 of the holes, to pass to and from the interior of the sock, and so carry off the moisture and perspiration. This sock device is preferably used inside the ordinary sock or stocking, and is first put over the foot, being 30 drawn on say by a heel portion or tag, at the back, and then the sock or stocking is drawn over it. Thus the sock consists mainly of 35 solid material such as referred to, with interspaced holes of substantial diameter, at substantial distances apart.

With regard to the material of which the sock is composed, wash leather or like leather is strong and pleasant, but substitutes for leather and like artificial materials may be 40 used or any material which is analogous and suitable, as regards its solidity, and is sufficiently flexible or pliable and pleasant to the touch may be used. Or, part may be made of one material and part of another.

45 The invention is illustrated in the annexed drawings wherein is shown a perspective view of one construction.

Referring to the drawings, *a* designates the sole piece, *b* the cap portion of the sock, and *c* a tag or heel part which serves for

55 putting the sock on, and is adapted to be disposed to the rear of the heel when the sock is in position on the foot. In this construction, the sock is preferably of one piece of soft leather, the cap portion being folded back on the sole piece *a*, and secured to the edges *d* thereof in any suitable manner, such as by stitching.

60 The soft leather like material is provided with a suitable number of apertures *e*, which are formed therein before it is formed into a sock, a suitable number being that shown in the drawings for the different parts of the sock. The aperture *e* in or adjacent to the tag or heel part *c*, is adapted to be disposed 65 beneath the ball of the heel when the sock is on the foot.

A sock made as above, is for use next to the foot itself, that is, the ordinary stocking or sock when worn, is put over the perforated soft leather sock, and therefore the improved sock of soft leather, which is preferably washable, may be termed an inner 70 sock.

75 It will be understood that other numbers of apertures to those shown may be formed in the different parts of the sock, and that the number shown is the approximate number for each part.

What is claimed is:—

80 1. An inner sock made of a single piece of material, comprising a sole portion having a reduced extension to form a heel tab, and a cap portion, the sole and cap portions being perforated.

85 2. An inner sock made of a single blank of material, said blank comprising a sole piece having a reduced extension to form a heel tab, said blank having a wing portion on the front, said wing being turned up and over and its edges stitched to the side edges of the sole piece to form a cap, the sole and cap being perforated.

90 95 In testimony whereof I have signed my name to this specification in the presence of two subscribing witnesses.

DENNIS MITCHELL.
